Primary Examiner — Cynthia M. Chin

(57) **CLAIM**

The ornamental design for a toy truck chassis, as shown and described.

DESCRIPTION

FIG. 1 is a top perspective view of the toy truck chassis showing our new design;

FIG. 2 is a rear bottom perspective view thereof;

FIG. 3 is a right side elevation view thereof; the left side elevation view is a mirror image of the right side elevation view;

FIG. 4 is a front elevation view thereof;

FIG. 5 is a rear elevation view thereof;

FIG. 6 is a top plan view thereof; and,

FIG. 7 is a bottom plan view thereof.

The broken lines are for the purpose of illustrating portions of the article that form no part of the claim.
